BOOKKEEPING PAD ASSEMBLY EMPLOYING SHINGLED STRIPS

Vincent Richard Youngquist, Whittier, Calif., assignor, by mesne assignments, to Burroughs Corporation, Detroit, Mich., a corporation of Michigan

Application June 21, 1955, Serial No. 517,012

1 Claim. (Cl. 282—22)

This invention relates to bookkeeping pad assemblies such as check books, receipt books, and the like, and is a continuation-in-part of my previously filed application for Bookkeeping Pad Assembly Employing Shingled Strips, filed May 20, 1954, Serial No. 431,154, now abandoned. It is particularly directed to devices of this type for facilitating the keeping of records and accounts.

An important object of this invention is to provide a relatively simple device, making it possible to write all necessary related records in a single writing operation so that information written on the original top sheet is transferred to underlying journal sheets by means of carbon paper. In this way, copying errors are completely eliminated because anything written on the original top sheet must of necessity be reproduced without change on the underlying journal sheets.

Another important object of this invention is to provide an improved form of check book or receipt book having a plurality of duplicate journal sheets bound at one edge, each journal sheet having a group of preshingled or pre-collated checks or receipts placed one upon the other in overlapping relationship and secured along their left-hand edges to the left-hand free edge of the journal sheet.

Another object is to provide a check book or receipt book of this type in which the binding for the journal sheets permits them to be opened to lie flat, and wherein an extension flap on the back cover may be inserted between the journal sheets to serve as a writing base.

Another object is to provide a device of this type wherein entries made upon each check are transferred by carbon paper to an employee's compensation record sheet and then to a payroll journal sheet below.

With the above and other objects in view, as may appear hereinafter, reference is directed to the accompanying drawings in which:

Figure 1 is a perspective view showing a preferred form of this invention, and illustrating a check book assembly in closed position;

Fig. 2 is a perspective view showing the check book assembly with the front cover opened and the back cover extension or flap in open position;

Fig. 3 is a perspective view showing the check book assembly with the first carrier sheet and preshingled checks in writing position, and showing the extended flap of the back cover being inserted under the second carrier sheet to provide a writing base;

Fig. 4 is a plan view, partly broken away, showing the check book opened to writing position;

Fig. 5 is a view showing a portion of the check book assembly on an enlarged scale and illustrating the use of a compensation record sheet interposed between the group of preshingled checks and the journal sheet; and

Fig. 6 is a sectional elevation, partly broken away, and taken substantially on the lines 6—6 as shown in Fig. 5.

The check book assembly generally designated 10 includes a front cover 11 and a back cover 12, joined by suitable binding means 13. A plurality of duplicate

2

journal sheets 14 are retained by the binding means 13, and can be opened to lie flat upon a table, desk, or other working surface. A group 15 of individual checks 16 in preshingled or precollated relationship is secured to the back face or under side of each journal sheet 14 along its free left-hand edge 17. A flap 18 which comprises an extension of the back cover 12 may be inserted between journal sheets 14, as shown in Fig. 3, to provide a writing base.

10 The group 15 of preshingled checks may be collated by hand before being attached to the journal sheets 14, or, if desired, may be produced on that form of check-shingling machine shown in the co-pending application of Dusenbury et al., Serial No. 249,884, filed October 5, 15 1951, now U. S. Patent No. 2,816,755, or Dusenbury et al., Serial No. 402,066, filed January 4, 1954, now U. S. Patent No. 2,816,756.

The upper edge of each check 16 extends beyond the upper edge of the next adjacent check, and this extending portion of each check is coated on its under surface with carbon-bearing material 19. This serves to transfer entries made on the upper part of each check to the journal sheet 14 below. Instead of carbon-coating portions of the back faces of the checks 16, a sheet of carbon paper, not shown, may be interposed between the check group 15 and the journal sheet therebelow.

In the embodiment of this invention shown in the drawings, the checks 16 are shorter than the journal sheets 14, and since the checks are attached to the free edge 17 there is an exposed space between the group 15 of checks 16 and the center binding means 13. In this exposed space are printed indicia 20 such as vertical lines dividing it into vertical columns and horizontal lines. The horizontal lines have the same spacing as the overlap of each check 16. The indicia 20 extend over substantially the full area of the back face of the journal sheet 14. Similar indicia 21 having aligning horizontal lines are printed on the front side of each journal sheet. This provides for columnar distribution, and permits utilization of both sides of each journal sheet 14.

In order to prevent transfer from the carbon-bearing strip 19 or the inserted sheet of carbon paper to the back face or underside of each journal sheet, when writing on the front face or upper side (that is, the right-hand 45 sheets as viewed in the drawings), a sheet of tissue paper 19a is inserted between the shingled group of checks or carbon paper and the underside of the journal sheet. When the journal sheet is opened for the purpose of writing on the checks 16, the tissue paper 19a is withdrawn. 50 In order that the tissue paper will not be inadvertently left in place, it is provided with a flap 19b which initially overlies the free margins of the checks. With this arrangement, the checks cannot be conveniently filled in without first removing the tissue paper 19a.

55 It should be observed that if a separate sheet of carbon paper is used, it may be omitted from the initial book of journal sheets and sets of checks, thus eliminating the need of the tissue sheets 19a. In such case the carbon paper is inserted under each set of checks just after the journal sheet is opened and just prior to filling out the checks.

If desired, the entire upper portion of all journal sheets 14, except the first and last, may be cut away to expose the box heading on the last or base journal sheet. 60 In this way, column titles can be identified by one writing, and this avoids the tedious work of manually entering the title of each column on each journal sheet 14.

To facilitate turning of the journal sheets 14, their upper extended corners may be beveled, as indicated by 65 14a. Also, the free margins of the journal sheets and the attached margins of the shingled stack of checks 16

may be provided with a row of perforations or slots 14b for use of a peg board, or the like.

In the use of the check book assembly shown in Figs. 1 to 4, the assembly is first opened to the writing position shown in Fig. 4, with the flap 18 inserted between the second and third journal sheets 14 to provide a writing base. This flap 18 also prevents smudging of the carbon on lower check groups under the flap 18. In addition, a sheet of paper, not shown, is inserted between the succeeding journal sheet and the shingled original entry sheets to avoid mark-off on the underside of such succeeding journal sheet.

The top check 16 in the group or series 15 is then filled out in the usual way, using a pen, ball pen, indelible pencil, or the like.

The date entered along the upper edge of the check 16 is automatically transferred by either the carbon coating 19 or carbon paper to the proper columns therebelow on the journal sheet 14. Horizontal distribution of the data written on the check may then be made by making the proper entries in the columns 21 on the same horizontal line. When all of the entries on the check 16 have been made, it is torn out of the assembly. This may be readily accomplished because each check is held in place along the perforated line 24. The check stubs 25 are connected to the tabs 26 along the perforated line 27. The tabs 26 are attached to the journal sheet by suitable adhesive.

The removal of the top check 16 in the series exposes each successive check therebelow and the operation may be repeated. When all of the checks 16 on the first journal sheet 14 have been removed, the second journal sheet 14 is swung back to writing position to expose its group of checks, and the flap is reinserted between the first and fourth journal sheets. This procedure is repeated until all of the checks are used.

Receipt forms may be substituted for the checks 16 to provide a receipt book instead of a check book. Both the checks and the receipt forms may be referred to as original entry documents. The indicia printed on the journal sheets would, of course, correspond to data of the type to be entered on the receipt forms. In other respects, the receipt book and check book are mechanically the same.

Fig. 5 shows how the improved form of check book or receipt book may be used in conjunction with loose data entry sheets 22 so that one writing operation, in making out the original entry document, serves automatically to transfer the data to two additional documents. The sheet 22 may comprise a compensation record sheet for a single employee. A different sheet 22 is inserted for each check 16. A sheet of carbon paper 23 transfers the data entry to the journal sheet 14. Horizontal distribution by columns is provided, as described above.

A tissue sheet, not shown, is also employed initially in

the arrangement shown in Fig. 5. As in the previously described arrangement, the tissue sheet is removed prior to filling in the checks.

While a particular embodiment of this invention has been shown and described, it is not intended to limit the same to the exact details of the construction set forth, and it embraces such changes, modifications, and equivalents of the parts and their formation and arrangement as come within the purview of the appended claim.

I claim:

In a device of the class described, the combination of: a front and a back cover; a group of duplicate rectangular journal sheets; means binding one vertical edge of the covers and each of the journal sheets forming a pad assembly that may be opened to lie flat; each of said sheets having a front and a back face, the front face of the sheet being exposed when the sheet is disposed to the right of said binding means, the back face of a sheet being exposed when the sheet is disposed to the left of said binding means; a group of shingled original entry sheets secured to the back face of each journal sheet at the free vertical edge thereof, opposite the binding means, whereby on opening of each journal sheet said entry sheets overlie the said journal sheets in a vertically overlapping relationship; each of said journal sheets having horizontal lines imprinted on both faces thereof, spaced apart a distance equal to the amount of overlapping of said entry sheets, the horizontal lines on the back face of each journal sheet being in substantial alignment with the horizontal lines on the front face of the succeeding sheet of said stack; each group of shingled original entry sheets being shorter than its journal sheet to expose a space on its journal sheet between the original entry sheets and the binding means, said exposed space of each journal sheet and the front face of its succeeding journal sheet being imprinted with vertical lines dividing same into vertical columns, thereby utilizing each journal sheet and the front face of its succeeding journal sheet for horizontal distribution of the data to be written on the original entry sheets; and means for transferring data entries on the original entry sheets to the journal sheet therebelow.
